Ralph E. McGaughy

Chas. J. Williamson

Attorney

UNITED STATES PATENT OFFICE.

RALPH E. McGAUGHEY, OF BLAIRSVILLE, PENNSYLVANIA, ASSIGNOR TO CONEMAUGH IRON WORKS, A CORPORATION OF PENNSYLVANIA.

BATHTUB TABLE.

Application filed January 2, 1925. Serial No. 278.

My invention relates to tables for supporting bath tubs while sifting thereon the powdered material for enameling and the object of my invention is to provide a simple and entirely efficient mechanism by which the tub may be caused to occupy the great number of positions necessary to present its surface properly in position for the sifting operation.

10 My invention consists in whatever is described by or is included within the terms or scope of the appended claims.

In the accompanying drawings:

Fig. 1 is a top plan view of a table embodying my invention;

Fig. 2 is a side elevation thereof;

Fig. 3 is an end elevation thereof.

The bath tub is placed upon a flat oblong platform, 10, which at its center rests upon a vertical shaft, 11, that is journalled to revolve upon a step bearing, 12, preferably having anti-friction balls that is fixed to the longitudinal center of a beam form support, 13, which at its opposite ends has upwardly projecting arms, 14, which hang from horizontal pivots or shafts, 15, in standards or uprights, 16. The two standards, 16, are connected by a pair of angles, 17.

It will be seen that the tub resting upon the platform, 10, may be turned horizontally on the vertical shaft, 11, or about a vertical axis and also by the lateral swinging of the support, 13, on the horizontal shafts, 15, may be moved on a horizontal axis and thus by its motion on these two axes any portion of its surface may be presented in the right position to receive the sifted material.

For rotating the platform, 10, upon the vertical axis, the vertical shaft, 11, has a bevel gear, 18, with which meshes a bevel pinion, 19, on a horizontal shaft, 20, which passes through one of the shafts, 15, which is tubular for the purpose, and beyond the adjacent standard, 16, has a hand wheel, 21, for revolving the shaft. Upon the tubular shaft, 15, to which the adjacent arm, 14, is fixed is a worm gear, 22, engaged by a worm, 23, on a horizontal shaft, 24, supported by a bracket or extension, of the adjacent standard, 16, upon which shaft, 24, is a hand wheel, 25, by which the worm may be revolved and thus the tub supporting platform,

10, by the swinging of the support, 13, may be tilted to the desired position. The worm gearing besides being an easily operated and powerful type of gearing has the further advantage that the meshing of the wheel with the worm holds the tub supporting platform in whatever angular position to which it may be moved.

What I claim is:

1. A work-table comprising a work receiving platform, and means for supporting said platform whereby it may be turned or rocked upon axes that intersect, and comprising a horizontal supporting member hung to turn upon a horizontal axis, a vertical shaft extending above said member between the ends thereof, gearing for swinging said supporting member comprising a worm, manual means to turn the worm, a worm wheel, a tubular shaft to which the worm wheel is fixed and gear for rotating said shaft comprising a horizontal crank-operated shaft extending through said tubular shaft.

2. A work-table comprising a work receiving platform, a vertical shaft at or near the center thereof, a horizontal beam below said platform having a stepped bearing for said shaft, pivots from which said beam is suspended at opposite ends, one of said pivots being tubular, a shaft passing through the tubular shaft and geared to said vertical shaft, a worm wheel on said tubular shaft and a worm meshing with said wheel.

3. A worktable comprising a work-receiving platform, a vertical shaft at or near the center thereof, a horizontal beam below said platform having on its upper side a stepped bearing for said shaft, the shaft being situated between said beam and said platform, a bevel gear on said vertical shaft, a pinion meshing with said gear, a horizontal shaft to which said pinion is secured which lies between said platform and said beam, pivots from which said beam is suspended, one of said pivots being tubular, and said horizontal shaft extending through the tubular pivot, gearing for swinging said beam, and gearing for rotating said horizontal shaft.

In testimony whereof I hereunto affix my signature.

RALPH E. McGAUGHEY.
